FREQUENCY CHANGING CIRCUIT
ARRANGEMENT

Maximiliaan Julius Otto Strutt and Aldert van der Ziel, Eindhoven, Netherlands, assignors to Hartford National Bank and Trust Company, Hartford, Conn., as trustee

Application July 2, 1946, Serial No. 680,964
In the Netherlands May 3, 1943

Section 1, Public Law 690, August 8, 1946
Patent expires May 3, 1963

6 Claims. (Cl. 250—20)

1

This invention relates to a circuit-arrangement for frequency-changing of electric oscillations by mixing them with locally generated oscillations, which comprises a discharge tube containing a cathode, an input electrode, an outlet electrode and one or more further electrodes having a positive bias, in which the (high-frequency) oscillations to be changed in frequency jointly with the local oscillations are supplied to the said input electrode and in which the frequency-changed (intermediate-frequency) oscillations are taken from the said output electrode.

The object of the invention is to provide means which permit a material reduction of the noise occurring in such circuit-arrangements. This noise, which particularly in the transmission of feeble signals is a source of great trouble, is due, on the one hand, to spontaneous voltage fluctuations (Brown's movement of the electrons) in the circuits connected to the discharge tube and on the other to current fluctuations in the discharge tube itself. The latter current fluctuations can be distinguished in emission-fluctuations (irregularities in the flow of emission of a cathode) and in subdivision-fluctuations (irregularities in the subdivision of the current between two or more electrodes having a positive bias). The noise due to these two latter causes is referred to respectively as the cathode-noise and as the subdivision-noise.

In the case of screen-grid tubes the subdivision-noise is, in general, considerably stronger than the cathode-noise. It may be observed in this connection that the subdivision-noise current in the anode circuit is equal and opposite to the subdivision-noise current in the screen-grid circuit. This is because an increase of the anode current owing to a variation of the subdivision of the current involves an identical decrease of the screen-grid current. The subdivision-noise consequently becomes manifest as an alternating current which passes from the anode to the screen-grid, but which does not occur in that part of the cathode conductor which is common to the anode circuit and to the screen-grid circuit. Due to this, the signal-to-noise ratio with screen-grid tubes is materially higher in that part of the cathode conductor than in the anode circuit.

It has been proposed before to make use of this circumstance to reduce the noise in the output circuit of a frequency-converter circuit by means of a positive (regenerative) feed-back for the frequency range occupied by the (high-frequency) oscillations to be changed in frequency,

2

the feed-back voltage being taken from the cathode conductor. This high-frequency feed-back considerably increases the signal voltage occurring in the input circuit. A high-frequency noise voltage correlated with the cathode noise is introduced at the same time in the input circuit. This noise voltage after frequency change, leads to an increase of the intermediate-frequency cathode-noise current passing in the output circuit. The increase of the cathode-noise current in the output circuit in consequence of the feed-back is, however, found on closer examination to be smaller than the increase of the signal current. In addition, the feed-back does not at all affect the subdivision-noise current in the output circuit, so that the ratio between the signal current and the subdivision-noise current increases materially. The resulting intermediate-frequency signal-to-noise ratio in the output circuit is consequently considerably increased by the feedback; in the case of highly intense feedback this ratio becomes nearly equal to the high-frequency signal-to-noise ratio in the cathode-conductor.

25 The circuit-arrangement described hereinbefore has the disadvantage that the required strong positive feedback makes it very difficult to avoid self-excitation when tuning through a wide frequency-range. It has been proposed before to obviate this disadvantage by using, at the same time, a negative (degenerative) feedback which compensates the action of the positive feedback so far as the tendency to self-excitation is concerned, but which does not disturb the favourable signal-to-noise ratio obtained by means of the positive feedback. The latter requirement is fulfilled if the feedback voltage for the negative feedback is taken from the intermediate-frequency output current, because in this case all the noise components of the output current are reduced by the negative feedback to the same extent as the signal. However, this again involves the disadvantage that the frequency of the feedback voltage for the negative feedback must be reduced to the frequency of the (high-frequency) signal to be changed in a separate frequency-changing stage. Though the second frequency-changing stage may also be used as an intermediate-frequency amplifier, the circuit-arrangement concerned is, in practice, highly involved.

According to the invention, the disadvantages involved by the said proposals are avoided by using a positive feedback for the frequency-band occupied by the intermediate-frequency oscilla-

tions, the feedback current or voltage being taken from a circuit in which the signal-to-noise ratio for the said frequency-band is higher than in the circuit of the output electrode.

For this purpose an oscillatory circuit coupled to the said circuit and tuned to the intermediate frequency may be included in the circuit of the input electrode. The feedback current or voltage is preferably taken from that portion of the cathode-conductor which is common to the circuits of the output electrode and of the said further electrode(s) having a positive bias.

An intermediate-frequency feedback arrangement has, according to the invention, important advantages over the high-frequency feedback arrangement proposed before. In particular, the arrangement, according to the invention, permits the employment of very strong feedback without danger of oscillation as the tuning frequency of the circuit is varied. If the stability is, nevertheless, still insufficient, or if the selectivity is excessively increased by the positive feedback, a negative feedback for the frequency-band occupied by the intermediate-frequency oscillations may be used at the same time, the feedback current or voltage for the negative feedback being taken from the circuit of the output electrode. This negative feedback permits eliminating, wholly or in part, the effect of the positive feedback with regard to the selectivity and the tendency to oscillation, while at the same time the favourable signal-to-noise ratio obtained by means of the positive feedback is not disturbed, because all the intermediate-frequency noise-components in the output circuit are reduced to the same extent as the signal by the negative feedback. If the two feedbacks are set up by the induction of a feedback voltage into an oscillatory circuit included in the circuit of the input electrode and tuned to the intermediate-frequency, the negative feedback is preferably proportioned in such manner that it brings about a damping of the said oscillatory circuit which is substantially equal to the negative damping produced by the positive feedback.

As has been pointed out hereinbefore, the prior circuit employing positive and negative high-frequency feedback required means to change the frequency of the negative feedback voltage to the frequency of the signal. The circuit, according to the invention, having positive and negative intermediate frequency feedback displays a great advantage over this prior circuit in that there is no requirement for changing the frequency of the negative feedback voltage.

As may be assumed to be known, the conversion conductance, that is to say the intermediate-frequency signal current in the circuit of the output electrode per volt of high-frequency signal voltage at the input electrode, is highly dependent upon the amplitude of the local oscillations supplied to the tube. It is thus found that if a high-frequency positive feedback is used a maximum signal-to-noise ratio is achieved in the output impedance if the conversion conductance is chosen to be low. For this reason it has been proposed before to choose the amplitude of the local oscillations and the operating voltages of the discharge tube in the case of a frequency-changing circuit having a high-frequency positive feedback, in such a manner that the conversion conductance amounts at the most to one fifth of the mutual conductance of the discharge tube for the high-frequency oscillations to be changed. This arrangement, however, does not

apply to the circuit-arrangement according to the invention in which an intermediate-frequency positive feedback is used and in which the amplitude of the local oscillations should, preferably, be such that the conversion conductance has, at least approximately, a maximum value.

In order that the invention may be clearly understood and readily carried into effect, it will now be set out more fully with reference to the accompanying drawing in which one embodiment of the invention is illustrated by way of example.

In the frequency-changing circuit shown on the drawing the high-frequency oscillations received by an aerial 1 are transmitted inductively to an input oscillatory circuit 2, which in series with a coil 3 coupled to a local oscillator 4 (shown diagrammatically) is included in the input circuit of a discharge tube 5. The discharge tube 5 comprises a cathode 6, a control-grid 7, a screen-grid 8 and an anode 9. The circuit of the anode 9 includes an oscillatory circuit 10 tuned to the intermediate frequency, which is coupled to a second intermediate-frequency circuit 11. The intermediate-frequency oscillations are taken from the circuit 11 via terminals 12 and 13. The cathode 6 is connected to ground in the usual manner via the parallel combination of a resistance 14 and a condenser 15, so that a suitable negative bias for the control-grid 7 is obtained. A positive bias is supplied to the screen-grid 8 and to the anode 9 via resistances 16 and 17. Jointly with the source of voltage these resistances are shunted by condensers 18 and 19 which constitute a short-circuit both for the high-frequency and for the intermediate-frequency oscillations.

According to the invention, the common part of the connections of the cathode 6 to the screen-grid 8 and to the anode 9 includes an inductance 20 which is coupled to an oscillatory circuit 21 which is tuned to the intermediate-frequency and which in series with the circuit 2 and the coil 3 is included in the circuit of the control-grid 7. The sense of the coupling between the coil 20 and the circuit 21 is such that a positive feedback for the intermediate-frequency oscillations is obtained. This feedback has the effect of materially increasing the signal voltage across the output circuit 10. The subdivision-noise current, which is set up by fluctuations of the subdivision of the current between the screen-grid 8 and the anode 9, does not pass, however, through the coil 20 and is consequently not biassed by the feedback. This results in a material increase of the signal-to-noise ratio.

It should be noted, however, that the addition of the circuit 21 by itself causes an increase of the noise-current in the anode circuit in consequence of the spontaneous potential fluctuations occurring in this circuit. If this increase were of the same order of magnitude as the subdivision-noise current, the use of a positive feedback would in practice no longer be effective. As the value of the said voltage fluctuations is determined by the impedance of the circuit 21 it is therefore desirable that this impedance should not be excessively high. A suitable value is that of 800 ohms, for instance.

The positive feedback by means of the coil 20 also gives rise to an increase of the selectivity of the circuit; this increase may be undesirable under certain conditions. In addition, the positive feed-back may have an unfavourable effect in some cases on the stability of the circuit. These disadvantages can be obviated by also us-

ing a negative feedback. To this end, the anode circuit of the circuit-arrangement shown in the drawing includes a coil 22 which is coupled to the circuit 21 in such sense as to secure a negative feedback for the intermediate-frequency oscillations. This negative feedback has again the effect of reducing the output voltage occurring across the circuit 10. However, as the coil 22 is included in the connection between the screen-grid 8 and the anode 9, so that the subdivision-noise current passes through the coil 22, the subdivision-noise voltage is reduced to the same extent as the signal voltage, so that the favourable signal-to-noise ratio obtained by means of the positive feedback is not disturbed. 15

In the embodiment of the invention hereinbefore described a tetrode is used to constitute the mixing tube. If desired, a tube having more electrodes, for instance a pentode or a hexode may be used. It is, however, essential in connection with the effect aimed at that the (high-frequency) oscillations to be changed and the local oscillations should be supplied to the same control-grid. If, for example, in the circuit-arrangement shown in the drawing the local oscillations would be supplied to a second control-grid provided between the anode and the screen-grid the cathode conductor would practically have not any intermediate-frequency current passing through it, so that the feedback by means of the coil 20 would have no effect. 30

What we claim is:

1. An electric circuit arrangement for mixing a first wave and a second wave, comprising an electron discharge tube having cathode, control grid, accelerating and anode electrodes, first means intercoupling said control grid and cathode electrodes and constituting a control grid-cathode circuit, second means intercoupling said accelerating and cathode electrodes and constituting an accelerating electrode-cathode circuit, third means intercoupling said anode and cathode electrodes and constituting an anode-cathode circuit, an output circuit coupled to said anode, means to apply said first and second waves to said control grid to develop in said output circuit an intermediate frequency wave, an impedance element connected in common to said anode-cathode and said accelerating electrode-cathode circuits, and means to couple said impedance element to said control grid-cathode circuit in regenerative relationship at said intermediate frequency to apply said intermediate frequency wave to said control grid. 35

2. An electric circuit arrangement for mixing a first wave and a second wave, comprising an electron discharge tube having cathode, control grid, accelerating and anode electrodes, first means intercoupling said control grid and cathode electrodes and constituting a control grid-cathode circuit, second means intercoupling said accelerating and cathode electrodes and constituting an accelerating electrode-cathode circuit, third means intercoupling said anode and cathode electrodes and constituting an anode-cathode circuit, an output circuit coupled to said anode, means to apply said first and second waves to said control grid to develop in said output circuit an intermediate frequency wave, an oscillatory circuit coupled in said control grid cathode circuit and tuned to the frequency of said intermediate frequency wave, an impedance element connected in common to said anode-cathode and said accelerating electrode-cathode 40

circuits, and means to couple said impedance element to said oscillatory circuit in regenerative relationship at said intermediate frequency to apply said intermediate frequency wave to said control grid. 45

3. An electric circuit arrangement for mixing a first wave and a second wave, comprising an electron discharge tube having cathode, control grid, accelerating and anode electrodes, first means intercoupling said control grid and cathode electrodes and constituting a control grid-cathode circuit, second means intercoupling said accelerating and cathode electrodes and constituting an accelerating electrode-cathode circuit, third means intercoupling said anode and cathode electrodes and constituting an anode-cathode circuit, an output circuit coupled to said anode, means to apply said first and second waves to said control grid to develop in said output circuit an intermediate frequency wave, a low impedance oscillatory circuit coupled in said control grid-cathode circuit and tuned to the frequency of said intermediate frequency wave, an impedance element connected in common to said anode-cathode and said accelerating electrode-cathode circuits, and means to couple said impedance element to said oscillatory circuit in regenerative relationship at said intermediate frequency to apply said intermediate frequency wave to said control grid. 50

4. An electric circuit arrangement for mixing a first wave and a second wave, comprising an electron discharge tube having cathode, control grid, accelerating and anode electrodes, first means intercoupling said control grid and cathode electrodes and constituting a control grid-cathode circuit, second means intercoupling said accelerating and cathode electrodes and constituting an accelerating electrode-cathode circuit, third means intercoupling said anode and cathode electrodes and constituting an anode-cathode circuit, an output circuit coupled to said anode, means to apply said first and second waves to said control grid to develop in said output circuit an intermediate frequency wave, a first impedance element connected in common to said anode-cathode and said accelerating electrode-cathode circuits, means to couple said first impedance element to said control grid-cathode circuit in regenerative relationship at said intermediate frequency to apply said intermediate frequency wave to said control grid in positive feedback relationship, a second impedance element coupled in said anode-cathode circuit, and means to couple said second impedance element to said control grid-cathode circuit in degenerative relationship at said intermediate frequency to apply said intermediate frequency wave to said control grid in negative feedback relationship. 55

5. An electric circuit arrangement for mixing a first wave and a second wave, comprising an electron discharge tube having cathode, control grid, accelerating and anode electrodes, first means intercoupling said control grid and cathode electrodes and constituting a control grid-cathode circuit, second means intercoupling said accelerating and cathode electrodes and constituting an accelerating electrode-cathode circuit, third means intercoupling said anode and cathode electrodes and constituting an anode-cathode circuit, an output circuit coupled to said anode, means to apply said first and second waves to said control grid to develop in said output circuit an intermediate frequency wave, an oscillatory circuit coupled in said control grid-cathode circuit 60

75

cathode circuit and tuned to the frequency of said intermediate frequency wave, a first impedance element connected in common to said anode-cathode circuit and said accelerating electrode-cathode circuit, means to inductively couple said first impedance element to said oscillatory circuit in regenerative relationship at said intermediate frequency to apply said intermediate frequency wave to said control grid in positive feedback relationship, a second impedance element coupled in said anode-cathode circuit, and means to inductively couple said second impedance element to said oscillatory circuit in degenerative relationship at said intermediate frequency to apply said intermediate frequency wave to said control grid in negative feedback relationship.

6. An electric circuit arrangement for mixing a first wave and a second wave, comprising an electron discharge tube having cathode, control, accelerating and anode electrodes, first means intercoupling said control grid and cathode electrodes and constituting a control grid-cathode circuit, second means intercoupling said accelerating and cathode electrodes and constituting an accelerating electrode-cathode circuit, third means intercoupling said anode and cathode electrodes and constituting an anode-cathode circuit, an output circuit coupled to said anode, means to apply said first and second wave to said control grid to develop in said output circuit an intermediate frequency wave, an oscillatory circuit coupled in said control grid-cathode cir-

cuit and tuned to the frequency of said intermediate frequency wave, a first inductive element connected in common to said anode-cathode circuit and said accelerating electrode-cathode circuit, a second inductive element coupled in said anode-cathode circuit, means to inductively couple said second inductive element to said oscillatory circuit in degenerative relationship at said intermediate frequency to provide a given damping for said oscillatory circuit, and means to inductively couple said first inductive element to said oscillatory circuit in regenerative relationship at said intermediate frequency thereby to counteract said given damping.
